G. MAIER

COMBINATION DESK AND DRESSING TABLE

Filed Dec. 31, 1927

*Inventor,
George Maier
By A. G. Schmitz.*

UNITED STATES PATENT OFFICE.

GEORGE MAIER, OF EVANSVILLE, INDIANA.

DESIGN FOR A COMBINATION DESK AND DRESSING TABLE.

Application filed December 31, 1927. Serial No. 24,724. Term of patent 14 years.

To all whom it may concern:

Be it known that I, GEORGE MAIER, a citizen of the United States, residing at Evansville, in the county of Vanderburg and State of Indiana, have invented a new, original, and ornamental Design for a Combination Desk and Dressing Table, of which the following is a specification, reference being had to the accompanying drawing, forming a part thereof, which is a perspective view showing my design.

I claim:

The ornamental design for a combination desk and dressing table, as shown.

In testimony whereof I affix my signature.

GEORGE MAIER.
